UNITED STATES PATENT OFFICE.

CARL E. METHUDY, OF ST. LOUIS, MISSOURI, ASSIGNOR, BY MESNE ASSIGNMENTS, TO
ALVIN D. GOLDMAN, OF ST. LOUIS, MISSOURI.

OVEN LIGHTER FOR GAS STOVES.

Application filed August 20, 1927. Serial No. 214,233.

This invention relates to improvements in oven lighters for gas stoves, and consists in the novel construction hereinafter disclosed.

An object of the invention is to provide 5 an improved device for automatically igniting the gas issuing from a burner remote from the flash pilot light of a gas stove, said device being so constructed as that the gas issuing from the burner to be ignited 10 is mixed with air and conducted through a tube to a point adjacent to a flame issuing from the flash pilot light.

Another object of the invention is to coordinate the orifice through which the gas 15 issues from the burner to be ignited to the tube so that, when the gas is ignited, the flame from said ignition point will be out of contact with the metal part of a tube through which the gas mixed with air is 20 conducted to a point where it is ignited by a flame issuing from the flash pilot light.

Another object of the invention is to provide a simplified and improved construction comprising a tube having its ends opening 25 toward and spaced from a gas burner and a flash pilot light respectively in order that gas issuing from the burner will pass through said tube with a proper admixture of air forming a combustible gas that will 30 be readily ignited when the flame from the flash pilot light is flashed adjacent to the end of the tube, but out of contact therewith, whereby the flame is conducted to a remote point to ignite the gas issuing from the 35 remotely disposed burner.

Other objects of the invention will appear from the following detailed description thereof taken in connection with the accompanying drawing, in which

40 Fig. 1 is a plan view of a gas stove showing a cluster of burners and with a portion of an oven burner disposed remotely therefrom.

Fig. 2 is a detail view of the ignition orifice leading from the oven burner showing the relation of the orifice to the end of the flame-conducting tube.

Fig. 3 is a detail view showing the relative position of the opposite end of said 50 flame-conducting tube in relation to the flame issuing from the flash pilot light.

In the embodiment of the invention illustrated in the drawing a gas stove of usual construction is illustrated. This comprises

a group of burners 1 connected into a manifold 2 through supply conduits 3. A flash pilot light of familiar construction is associated with the burners 1, being associated in the group of burners in such a position that a flame is flashed therefrom across the surface of the burners for igniting the same. The said flash pilot light includes a burner tip 4 that is supplied with gas through a conduit 5 connected into the manifold 2, the flow of gas through the conduit 5 being controlled by a valve 6 of familiar construction. It will be understood that the valve 6 is normally in adjustment to admit only a sufficient amount of gas to pass through the burner tip to provide a 70 pilot light and that, when it is desired to create a flash to ignite gas issuing from any of the group of burners 1, the valve is opened to a greater extent so that flames flash from the burner tip through the several orifices 75 therein and outwardly through openings 7 in the casing 8 that encloses the pilot light.

An oven burner 9 that is provided with a plurality of the usual gas issuing orifices 10 is located at a point remote from the group of burners 1, said burner being supplied from the main manifold 2 through a valve-controlled conduit 11. The burner 9 is provided also with an orifice 12 through the side wall thereof, which orifice 12 is positioned so that, when the gas issuing therefrom is ignited, a flame is created which burns with substantially complete combustion and out of contact with a flame-conducting tube.

The flame-conducting tube 13 extends from a point spaced from the burner 9 to a point spaced from the pilot light, said tube 13 being supported in any convenient manner by the stove construction and, in the embodiment illustrated, by a strap 14 connected with a portion of the burner 9 and with the tube. The position of the tube 13 is such that the end within the vicinity of the pilot light burner is preferably arranged in a 95 plane below the plane of the flame issuing from the pilot light burner. This relative arrangement of the flame from the pilot light burner and of the end of the tube is clearly illustrated in Fig. 3 of the drawing. 100 The outer end of the tube 13 is spaced only a sufficient distance from the orifice 12 to permit the gas issuing from said orifice to 105

mix with a quantity of air forming an admixture of a highly combustible character, which enters the tube 13 and is conducted to a point within the vicinity of one of the flash flames issuing from the pilot light burner. The spacing of the end of the tube 13 from the orifice 12 is such also that, when the gas is ignited that issues from the orifice 12, a flame is produced which burns 10 in contact with air and therefore provides for complete combustion thereof out of contact with the end of the tube. By arranging the orifice 12 at a position below the axis of the tube 13, when the flame burns, 15 it will burn with a point substantially coaxial with the tube 13, but out of contact with said tube. If the construction was such that the flame issuing from the orifice 12 came in contact with the tube 13 there would 20 form a deposit of carbon and there would also be incomplete combustion of the flame forming carbon monoxide. It is, therefore, an important feature of the present invention to dispose the tube 13 so that the outer 25 end thereof is spaced from said orifice 12 and at the inner end thereof is so disposed in relation to the flame issuing from the flash pilot light that neither flame, that is, from the flash pilot light nor from the burner, 30 contacts directly with the metal of the tube.

In operation, the valve 6 of the flash pilot light burner is opened, and the gas supply to the burner 9 is opened. The gas issuing from the orifice 12 enters the tube 13 together 35 with an admixture of air and is conducted to the opposite end where it is ignited from the heat created by the flash flame traversing above the end of said tube. When the flame ignites, it is conducted backwardly through 40 the tube igniting the gas issuing from the orifice 12 from which it is propagated around the burner to each of the orifices of the burner being ignited serially.

While the invention has been shown as embodied in a gas range or stove comprising burners of familiar construction and as applicable for lighting an oven burner, it will be understood that the invention may be varied within equivalent limits without departure from the nature and principle thereof. Accordingly, I do not restrict myself to the exact construction shown and described,

but what I claim and desire to secure by Letters Patent is:—

1. A device of the character described comprising a flash pilot light, a burner spaced from the pilot light and provided with a gas outlet, and a tube supported between the burner and the pilot light having open ends spaced from both and arranged to receive and conduct gas issuing from the burner toward the pilot light. 55

2. A device of the character described comprising a pilot light adapted to flash a flame outwardly therefrom, a burner spaced from the pilot light and provided with a gas outlet, and a tube supported between the burner and the pilot light and having an open end below the plane of the flame issuing from the pilot light and an open end arranged to receive and conduct gas issuing from the burner toward the pilot light. 60
70

3. A device of the character described comprising a pilot light, a gas burner having a gas outlet orifice through a lateral wall thereof, and a tube having an open end, the axis of which is above said gas outlet, and adapted to receive gas from said outlet and spaced therefrom, said tube extending toward and terminating at a distance laterally 75
80 from said pilot light.

4. A device of the character described comprising a pilot light having a flash flame opening, a burner having a gas outlet, and a tube supported between said burner and said pilot light and having open ends spaced from both. 85

5. A device of the character described comprising a flash pilot light, a gas burner having gas outlets through the wall thereof, and a gas outlet opening in another direction, in combination with a tube having an open end adjacent to and spaced from said last-named outlet and having its opposite end opening toward and spaced from said pilot light. 90
95

6. A device of the character described comprising a flash pilot light, a burner, and a tube arranged to confine gas, said tube being located between said burner and said pilot light and having open ends opening toward and spaced from said pilot light and burner respectively. 100
